J. DAVIES

OIL FUEL BURNER FOR USE IN FURNACES, BOILERS, AND THE LIKE

Filed May 11, 1922

Patented Jan. 22, 1924.

1,481,419

UNITED STATES PATENT OFFICE.

JOHN DAVIES, OF DARLINGTON, ENGLAND, ASSIGNOR TO THE DAVIES FUEL BURNERS LIMITED, OF STOCKTON-ON-TEES, DURHAM, ENGLAND.

OIL-FUEL BURNER FOR USE IN FURNACES, BOILERS, AND THE LIKE.

Application filed May 11, 1922. Serial No. 559,995.

To all whom it may concern:

Be it known that I, JOHN DAVIES, of Marlborough House, The Mead, Darlington, in the county of Durham, England, engineer, a subject of the King of Great Britain and Ireland, have invented a certain new and useful Improved Oil-Fuel Burner for Use in Furnaces, Boilers, and the like, of which the following is a specification.

10 This invention relates to oil fuel burners for use in furnaces, boilers and the like.

The object of this invention is to provide an improved oil fuel burner in which the oil fuel is more completely atomized than 15 has previously been the case.

An oil fuel burner for use in furnaces or the like made in accordance with this invention is characterized in that it is provided with an annular jet of fuel, a forcing and 20 atomizing jet within the said annular fuel jet, and a second atomizing jet under pressure surrounding the said annular fuel jet.

In the preferred form the improved burner comprises a tubular casing having 25 an orifice at one end to form a nozzle and containing two tubes concentric with each other and with the tubular casing adapted to form a passage between said tubes, and another passage between the outer tube and 30 the casing, means for supplying oil to the passage between the concentric tubes, means for supplying compressed air, steam or the like to the passage between the outer tube and the casing, means for supplying compressed air, steam or the like to the interior 35 of the central tube, means to ensure that the air or the like in the passage between the casing and the outer concentric tube issues from said passage at the nozzle in a jet at

40 right angles to the axis of said tube and casing, means to ensure that the air or the like in the central tube issues from said tube at the nozzle in an annular jet at an angle inclined from the axis of said tube to meet 45 the outer jet of air at an obtuse angle, means to ensure that the oil in the passage between the two concentric tubes issues from said passage in an annular jet between the two

50 jets of air, steam or the like so as to be atomized, means for providing a supply of air or steam to the oil before it reaches the nozzle to partially break up or gasify said oil, and means for regulating the supply of oil at the nozzle.

55 The preferred form of oil fuel burner

constructed in accordance with this invention is illustrated in longitudinal section on the drawing filed herewith.

a is the tubular casing made in two parts screwed together having on one end a cap a' provided with an orifice b to form a nozzle. The casing contains two tubes c and d concentric with each other and with the tubular casing, the tube d being made in two parts screwed together. The tubular 60 casing contains an annular chamber e to which oil is fed through a supply pipe f. The oil passes from the chamber e through the passage g between the concentric tubes c and d to the nozzle. The casing a also contains an annular chamber h to which compressed air, steam or the like is admitted by the supply pipe i. The nozzle ends of the tubes c and d are provided with hollow cones c' and d' respectively. The compressed air in the chamber h passes through the vents j to the annular passage k between the tube c and the casing a and impinges on the flat inner surface of the cap a' being diverted at right angles to the axis of the casing through the space between the cap and the end of the cone c'. A solid cone l is fitted in the end of the tube d inside the hollow cone d'. Compressed air, steam or the like is supplied to the interior m of the tube d through a suitable connection on the end d'. The compressed air, steam or the like passes through the vents l' in the base of the cone l and issues in an annular jet between the cone l and hollow cone d' said jet being inclined from the axis of the tube d, the inclined faces of the cones effecting this inclination of the jet so that it meets the jet of air from the passage k at an obtuse angle. The oil from the passage g issues between the cones c' and d' to the point of contact of the two jets of air, steam or the like, being drawn along the passage g by the suction of said jets.

The oil is completely atomized by reason of the air or steam jet issuing from the passage m, cutting the air jet from the passage k at an obtuse angle at the point of contact of the jets of air and oil. The atomized oil then issues in a jet through the orifice b in the cap a' and takes the general direction of the jet of air, steam or the like from the passage m. Air or steam from the passage m may issue through vents n in the tube d to the passage g so that the oil contained 110

therein may be partially atomized before reaching the nozzle. Leakage of oil from the chamber *e* is prevented by a stuffing box *o* and gland *p*, and packing *q*. A boss *r* is screwed on to the end of the tube *d* and is keyed to a hand-wheel *s*, being provided with a flange *r'* abutting against the gland *p*. Lateral movement of the boss and hand-wheel is prevented by a cap *t* enclosing the flange *r'*. When the hand-wheel and boss are revolved the tube *d* is advanced towards or receded from the nozzle so that the size of the passage between the cones *c'* and *d'* is regulated for the supply of oil to the nozzle. The inner face of the cone *c'* forms a seat for the cone *d'* so that the passage may be entirely closed if necessary.

What I claim and desire to secure by Letters Patent is:—

1. Improved oil fuel burner for furnaces of various kinds utilizing liquid fuel comprising a medial tubular casing with a nozzle projecting an annular jet of fuel, an inner tubular casing concentric thereto, a passage between said medial tubular casing and said inner tubular casing, an outer tubular casing concentric with the before-mentioned medial tubular casing and a passage be-

tween said outer tubular casing and said medial tubular casing and means for supplying compressed air to a passage between the said inner tubular casing and said medial tubular casing and means for ensuring that the air, steam in the passage between the medial tubular casing and the inner tubular casing issues at the nozzle in an annular jet at an angle inclined from the axis of the said tubular casing to meet the outer jet of air at an obtuse angle.

2. Improved oil fuel burner for furnaces of various kinds utilizing liquid fuel comprising a tubular casing having a cap and an orifice at one end to form a nozzle and containing two tubes concentric with each other and with the tubular casing, an annular chamber to which oil is fed through a supply pipe, an annular chamber to which compressed air is admitted by a supply pipe, hollow cones to the nozzle ends of the concentric tubes, a solid cone fitted in the end of the tube inside the hollow cone, means for preventing leakage of oil and means for regulating the supply of oil to the nozzle.

In testimony whereof I have signed my name to this specification.

JOHN DAVIES.
